DESIGN FOR A RESTAURANT SEAT

Leonard W. Lowther, Merchantville, N. J., assignor to Horn and Hardart Baking Co., Philadelphia, Pa., a corporation of Pennsylvania

Application April 6, 1940, Serial No. 91,521

Term of patent 14 years

To all whom it may concern:

Be it known that I, Leonard W. Lowther, a citizen of the United States, residing at Merchantville, in the county of Camden and State of New Jersey, have invented a new, original, and ornamental Design for Restaurant Seats, of which the following is a specification, reference being had to the accompanying drawing, forming part thereof.

I claim:

The ornamental design for a restaurant seat, substantially as shown.

LEONARD W. LOWTHER.
